UNITED STATES PATENT OFFICE.

SAMUEL H. DOLBEAR, OF SAN FRANCISCO, CALIFORNIA.

STORAGE BIN, DEN, AND THE LIKE.

1,279,089.

Specification of Letters Patent. Patented Sept. 17, 1918.

Application filed July 3, 1915. Serial No. 37,978.

To all whom it may concern:

Be it known that I, SAMUEL H. DOLBEAR, a citizen of the United States, residing at San Francisco, in the county of San Francisco and State of California, have invented certain new and useful Improvements in Storage Bins, Dens, and the like, of which the following is a specification, reference being had therein to the accompanying drawing.

This invention relates broadly to storage bins, dens, and the like, and more specifically to means for effecting the discharge of the contents thereof.

15 The object of the invention is to provide simple and effective instrumentalities for accomplishing the emptying of a bin, or the like.

Another object is to provide the bottom of 20 a bin with a tiltable portion so that when raised on its fulcrum, it will at the same time dispose the mass supported thereon so that said mass will attain a certain momentum during its discharge, whereby the bin 25 may be quickly and thoroughly emptied of its contents.

Still another object is to provide a construction of such form that it is unnecessary to move the bin itself in order to effect 30 a discharge therefrom of its contents. For this reason, there is a considerable economy of space over the character of bins now in use which include an inclined bottom.

The invention in general seeks to provide 35 a bin-structure which is particularly adapted for use in storing ore and the like and which structure, from an operative standpoint, will in practical use possess a high degree of efficiency, durability and convenience and 40 which, structurally considered, will be of great simplicity.

Involved in the invention are other objects and advantages which will be obvious from the annexed drawings and from the following description.

The invention resides broadly in the features of construction and in the correlative aggroupment of its parts, all as exemplified in the structure hereinafter set forth, and the scope of application of which will be indicated in the claim hereto appended.

In order that the invention may be comprehended readily, drawings illustrating some of the possible embodiments and utilizations of the same are hereto appended as

a part of this disclosure; it being manifest that other possible embodiments and utilizations (employing the underlying principles of my invention) fall within the spirit thereof and within the objects contemplated thereby.

In these drawings:

Figure 1 is a view in rear elevation of a storage bin constructed in accordance with one embodiment of my invention;

Fig. 2 is a view in vertical transverse section of the same on the line 2-2, Fig. 1;

Fig. 3 is a similar view showing the parts in a different position;

Fig. 4 is a top plan view of a modification;

Fig. 5 is a view in vertical transverse section of this modified form, on the line 5-5, Fig. 4;

Fig. 6 is a similar view thereof with the parts shown in a different position; and

Fig. 7 is a view in vertical transverse section of another modification.

Referring to these drawings, the reference-character 1 designates the bin or den, generally, comprising a top portion 2, front 80 and rear portions, 3 and 4, respectively, and a bottom portion 5. The bin may be of any required form, material and dimensions. In this instance, the bin is shown as rectangular in form and as built of metal.

The bottom-portion 5 is, preferably and as shown, hinged at 6; that is, adjacent the front portion 3. The latter is provided with a discharge-opening 7 which is controlled by a slidable gate or door 8. A chute 9 directs the contents from said opening.

Means are provided for actuating the bottom-portion and, in the embodiment illustrated by way of example in Figs. 1 to 3, such means include a motor comprising a pair of elevating ropes or cables 10 which are secured to lugs 11 at opposite ends of the bottom portion and pass upwardly through the top of the bin and over juxtaposed pulleys or sheaves 12 and 13. These ropes or cables may be connected to a means for tilting the bottom in relation to the side sections, and here diagrammatically indicated by the letter W.

As a means for holding the mass of ore or other contents of the bin away from the inner surface of the rear portion thereof, a mass-moving shield 14 is provided. This, at its lower end is pivotally connected to the

tiltable bottom and includes two members 15 and 16, pivotally connected together, as at 17, the member 16 being pivotally attached, as at 18, in the upper rear corner of 6 the bin.

Operation: Assuming that the bin has been filled with ore, say, through an opening (not shown) in its top, the gate 8 is raised. Thereupon, the lifting ropes 10 are drawn 10 forward by their motor. These, in turn, tilt the bottom to the position shown in Fig. 3. The mass slides down in Fig. 3. The mass slides down the inclined surface, thus provided, through the opening 7, onto the chute 15 9 and to a suitable receptacle juxtaposed thereto. As the bottom raises, the members of the shield 14 are caused to be brought into angular relation and the member 15 tends to throw forward the portion of the mass resting against it.

The bottom may be repositioned to normal by gravity due to its own weight after the ropes 10 are slackened.

In Figs. 4 to 6, I have shown a modification of the structure. This includes a movable bottom 19 hinged at 20 and carrying at its free end a pivoted shield-member 21. In this instance, also, a different form of device is utilized for moving the bottom. 30 Preferably and as shown, this comprises a motor 22, or a pair of motors, each consisting of a cylinder 23 and a fluid-actuated piston 24 movably disposed therein.

In Fig. 7, I have shown another modification. This includes a tiltable bottom 25 actuated by a motor M, similarly as in the modification just described. In this instance, however, a weight-actuated apron 26 is employed. This is secured to the free 40 end of the bottom 25 and passes over a sheave 27 and carries at its other end a weight 28 outside of the bin. As the bottom rises, the weight pulls the apron up-

wardly. The mass is, by this means, always held away from the rear portion of the bin. 45

From the foregoing, it will be perceived that I have succeeded in devising a bin-structure having a mass-supporting member which is tiltable on its hinge by means of a motor and having, also, a mass-holding 50 shield which is movable with the supporting-member and operating, always, to hold the mass away from the rear wall of the bin. The structure is well adapted to achieve the several objects and ends in view; 55 and it is compact in form and easily manipulated.

As the invention is susceptible of a considerable range of modification without departure from the spirit thereof, it is intended that all matter in the foregoing description and shown in the accompanying drawings shall be regarded as illustrative and not in a limiting sense. 60

What I claim is:

A stationary bin structure comprising side and end sections and a bottom section joined to form a receptacle for materials; one of said sections being provided with an exit for the materials; said bottom section 70 being hingedly connected at one end, to a portion of the receptacle and normally lying in a horizontal plane; the other end of said bottom section being movable vertically to expel materials through the exit; and a section 75 hingedly connected to the bottom section and co-operating with one of the other sections to expel materials through the exit when the bottom is lifted.

In testimony whereof I affix my signature 80 in presence of two witnesses.

SAMUEL H. DOLBEAR.
